ELECTRICAL LIGHTING UNIT

Harry Yale Mageoch, Havertown, Pa., assignor to
Electric Service Manufacturing Co., Philadel-
phia, Pa., a corporation of Pennsylvania

Application October 21, 1949, Serial No. 5,628

Term of patent 14 years

(Cl. D48—23)

To all whom it may concern:

Be it known that I, Harry Yale Mageoch, a citizen of the United States, and a resident of Havertown, State of Pennsylvania, have invented a new, original, and ornamental Design for an Electrical Lighting Unit, of which the following is a specification, reference being had to the accompanying drawings, forming a part hereof, wherein:

Figure 1 is a perspective view of an electrical lighting unit, showing my new design;

Figure 2 is a side elevational view thereof;

Figure 3 is a bottom plan view;

Figure 4 is a top plan view; and

Figure 5 is a side elevational view similar to Figure 2 showing the body turned in a different position.

I claim:

The ornamental design for an electrical light-
ing unit, as shown.

HARRY YALE MAGEOCH.
